ATTORNEY

UNITED STATES PATENT OFFICE

BERNARD W. SHOCKLEY, OF BRIDGEWATER, MASSACHUSETTS

PUZZLE DISPLAY DEVICE

Application filed May 21, 1930. Serial No. 454,377.

This invention relates to a puzzle of the jig-saw type and more particularly to a novel means for presenting the puzzle to the tray so that, before the puzzle is actually worked, 5 the picture which is represented thereby may be viewed and the one purchasing or receiving the puzzle may therefore gain a general idea of the result to be obtained by a proper assemblage of the component units or pieces 10 of the puzzle, and in this connection the invention has as its object to provide a puzzle which may be conveniently handled and which may be given to patients in hospitals, and in sanitariums, for the patient's amusement and as a pass-time novelty.

This invention also consists in certain other features of construction and in the combination and arrangement of the several parts, to be hereinafter fully described, illustrated 20 in the accompanying drawing, and specifically pointed out in the appended claim, it being understood of course that minor changes may be made so long as they fall within the scope of the claim.

25 In describing my invention in detail, reference will be had to the accompanying drawing, wherein like characters denote like or corresponding parts throughout the several views, and in which:—

30 Figure 1 is a plan view of the puzzle embodying the invention.

Figure 2 is a transverse sectional view taken substantially on the line 2—2 of Figure 1.

35 Figure 3 is a perspective view of a part of the container for the puzzle.

The invention contemplates, generally speaking, in the provision of a puzzle of the jig-saw type in which a number of pieces, 40 of various marginal contours are to be assembled in marginal registration so as to form a true rectangular picture, portions of which picture are represented upon the faces of different ones of the said pieces and, the 45 initial arrangement of these pieces in assembled relation within a container in the nature of a shallow tray provided with a transparent lid.

In the drawing the numeral 1 indicates the 50 body of a shallow box which may be of card-

board or any other material found suitable for the purpose and which is preferably of the oblong rectangular form shown most clearly in Figure 1 of the drawing. Within the body 1 there is arranged, in inverted position, a tray 2 which is preferably of the same material as the body 1 and this tray is preferably formed from a rectangular blank and incisions are made in the corners thereof, and the material turned down to provide the side and end walls of the tray, and it will be observed by reference to Figure 2 that the tray is of less depth than the body 1 of the box and is disposed within the box in inverted position. The tray bottom is therefore presented upwardly and arranged upon the same are the component pieces 3 of a picture which is produced by the proper assemblage of these pieces.

The pieces 3 are formed from card-board or thin wood and each piece will of course bear upon its face which is uppermost when the pieces are arranged upon the bottom of the tray 2, a portion of the composite picture.

The cover member of the box is indicated by the numeral 4 and is in the nature of a rectangular frame of paste-board or other material suitable for the purpose and provided with side and end flanges 5, which flanges constitute the side and end walls of the said cover, and the cover is so proportioned as to adapt it to be fitted down over the body 1 in the manner clearly shown in Figure 2. In order that the picture may be viewed, when the pieces 3 are properly assembled to form the complete picture, a sheet 6 of isinglass or transparent paper or other material of a transparent character is disposed over the assemblage of pieces and confined at its margins by the marginal portions of the cover 4 which surround the opening in the cover.

In practice, the component pieces of the picture are properly assembled so as to form the composite or complete picture by properly arranging the pieces within the body of the box upon the bottom of the tray 2, and the cover is then applied to the said body, the transparent sheet 6 having been first arranged over the assemblage of pieces. The

- device is then in condition to be placed upon the market and the one receiving the device will, after careful consideration of the picture gain a general impression as to the nature thereof, remove the pieces and likewise the tray 2 and then turn the tray right side up and, at this time, proceed with his or her efforts to so arrange the pieces as to form the composite picture, in the tray.
- 10 It will be understood of course that some of the pieces or blocks 3 will have right line sides as well as irregular sides, and that these blocks or pieces are the ones which are to constitute the marginal pieces of the completed picture and their straight or right line edges or sides will then abut against the inner sides of the walls of the tray.

What I claim is:—

- 20 A puzzle of the class described comprising a box, a cover for the box comprising a frame to fit over the upper side of the box, and a transparent sheet within the frame, a tray disposed in inverted position in the box, and a plurality of picture blocks of various 25 marginal contours adapted, when properly assembled, to form a complete picture of a marginal contour to fit within and fill the tray, the blocks being initially properly assembled upon the bottom of the tray, and the 30 tray, after removal of the blocks, constituting means within which the blocks may be reassembled.

In testimony whereof I affix my signature.
BERNARD W. SHOCKLEY.
